LOCKING DEVICE

William A. Heidman and William A. Heidman, Jr.,
Grand Rapids, Mich.

Application February 9, 1942, Serial No. 430,064

7 Claims. (Cl. 292—252)

This invention relates in general to a locking device which is particularly adapted for use in connection with a closure member having a swinging or lateral movement. While our invention may be applied to various devices, we have preferred, for purposes of illustration, to show the mechanism as applied to the pivotally mounted swingable ventilating window of an automobile door.

The mechanism in general consists of a pin mounted on the frame of the door and a housing mounted on the movable window. An opening is provided through the window at an edge thereof through which the pin passes when the window is in closed position. Within the housing a ball retainer is located which is adapted to hold a plurality of balls between which the end of the pin is received. A yielding force is applied to the balls which is transmitted to the pin, thereby frictionally engaging and gripping the pin to prevent opening of the window.

Devices of this general nature embodying the frictional engagement of balls against a pin have been known heretofore, but their application have been limited to devices wherein a straight line movement is had between the ball retainer and the pin. No difficulties arise in the use of mechanism of this general nature when the locking mechanism is to be moved in a straight line away from or toward the pin providing the part carrying the locking device is freely movable relative to the pin, but when such a device is applied to a closure member adapted to swing about an axis, certain difficulties must be overcome because the locking device moves in an arcuate or inaccurate path with respect to the pin and is constantly changing its position in a lateral direction with respect thereto. It will be obvious, then, that former devices of this character could not be used on a swinging member because the locking device does not approach the pin with a straight line movement but rather from an angle and yet in a closed and locked position of the member the lock and the pin should be in direct alignment.

Our invention then resides in the novel mechanism which permits a lock of this character to be used on a swinging closure member and which permits the lock to approach the pin from an angle. Also the lock is arranged to automatically center itself on the pin in spite of inaccuracies in assembling the window in the frame. The various details of structure and advantages arising therefrom will appear more fully as the description proceeds, such description being made

more clear when considered in connection with the accompanying drawing wherein:

Fig. 1 is a horizontal section through an automobile door showing the ventilating window section in closed position with our invention attached thereto, the window being shown in open position in dotted lines.

Fig. 2 is a fragmentary side elevational view of the door and window therein with certain parts broken away to show details.

Fig. 3 is an enlarged sectional view taken on a horizontal plane through the locking device of our invention.

Fig. 4 is a section through the device taken substantially on the plane of line 4—4 of Fig. 3, and

Fig. 5 is a section through the device taken substantially on the plane of line 5—5 of Fig. 3.

Referring now more particularly to the drawing, the automobile door itself is generally indicated at 1 and the portion of the window which is swingably mounted and may be used for ventilating purposes is indicated at 2. This portion of the window is mounted on a channel frame 3 in the usual manner which has a pivot pin 4 located at its upper side and another pivot pin 5 extending downwardly from its lower side into the door frame. In accordance with usual construction, the door frame is provided with a channel member 6 within which is located a length of yieldable material 7 such as rubber. A portion of this material extends outwardly as at 8 around the ventilating window against which the edge of the window abuts when in closed position to insure a tight seal. The structure thus far is in accordance with recognized practice.

At the lower part of the window and beneath the channel 6 a bracket 9 is secured through which the pivot pin 6 passes. Spaced downwardly from the bracket a collar 10 is securely held on the pivot pin by means of a nut, and a coiled compression spring 11 bears at one end against the collar and at its other end against the bracket 9. This construction is conventional and is for the purpose of creating frictional resistance to pivoting of the window and is utilized with this invention as hereafter described.

In the construction of the lock an arm 12 extends outwardly from the door frame to which the pin 13 is attached as clearly shown in Fig. 3. A lock housing 14 is then fastened to the inner side of the window by means of a narrow tubular extension 15 which passes through and snugly engages the sides of an opening through the

window. The outer end of this extension is flanged as at 16 whereby the housing is securely held in contact with the window.

Within the housing itself the ball retainer 17 is located which is of a frustro-conical shape and has a plurality of spaced apart openings therein to receive the balls 18. The ball retainer is continued outwardly into an elongated extension 19 and a central opening extends upwardly in the ball retainer and extension to receive the pin 13. The lower end of the opening is flared outwardly from the narrow portion of the opening as shown at 20 to thereby provide a funnel-shaped entrance to receive the pin.

A collar 21 surrounds the ball retainer and has a tapered opening to receive the retainer with the balls thereon. A compression spring 22 surrounds the extension 19 and bears at one end against the shoulder provided between the extension and the main body of the retainer and at its other end against the upper end of the housing 14 thereby normally urging the balls against the sides of the opening in the collar 21. Such a force against the balls will urge them inwardly thereby maintaining a gripping action against the pin when it is located as shown in Fig. 3.

A button or knob 23 surrounds the housing 14 and has passed therethrough the pin 24 as shown in Figs. 3 and 4. The extension 19 of the ball retainer is provided with an opening 25 which loosely receives the pin 24 and since there is a considerable space between the collar 21 and the sides of the housing 14, the ball retainer and the collar will be free to move in a lateral direction with respect to the pin 13 about the pin 24. The spring 22 also has lateral clearance to permit this movement.

From the position of the device as shown in Fig. 3, if it is desired to open the window the knob 23 will be grasped and a pull exerted thereon. This pull will move the pin 24 outwardly against an edge of the opening 25, from which point the ball retainer 17 will be moved against the force of the spring 22. As the ball retainer moves the gripping pressure of the balls 18 against the pin 13 will be released and the force of the pull will then swing the window to open position. It is to be noted here that before any movement of the window can take place the frictional resistance as provided by the compression spring 11 must be overcome.

Still further it is to be noted that immediately upon release of the pin 13 and as the window is opened, a change of relationship takes place between the ball retainer and the end of the pin since the ball retainer is being moved in an arcuate path. The retainer and the collar associated therewith will be free to move in a lateral direction, to thereby prevent binding and permit the window to be freely opened. Also the spring 22 is such that when it is completely compressed it acts as a stop member to prevent the ball retainer from being moved beyond the confines of the collar, which would otherwise permit the balls to drop out of their sockets. Also it is to be noted that the diameter of the pin 13 is considerably less than the opening through the tubular extension 15. This is necessary to permit the window to swing free of the pin in its arcuate movement. The central opening in the ball retainer 17 and its extension 19 is larger than the pin 13 which permits the parts to function properly in spite of inaccuracies of alignment and positioning.

During the opening movement the frictional

resistance caused by the spring 11 at the window pivot acts to insure full release of the balls 18. If there were no resistance to movement the balls would relieve their frictional grip of the pin 13 only enough to permit them to slide thereon. In order to overcome the resistance caused by the spring 11 the spring 22 will be considerably compressed, probably to its limit, thereby completely releasing the balls 18 from the pin 13.

10 After the window has been opened and it is desired to close it a push against the knob 23 will be transmitted to the window either by its bearing at one end against the window or by the shoulders 26 thereof bearing against the end of the housing 14. It is to be noted that when the knob is seated in this way the pin 24 is in an intermediate position in the opening 25 so that upon a closing of the window the pin 24 will not engage any part of the extension 19 and thus no force will be exerted against the ball retainer. Also the clearance within the knob is sufficient to avoid contact with the head of the extension 19. As the mechanism approaches the end of the pin 13 the wide opening in the tube 15 will receive the pin at an angle and the funnel shaped opening 20 in the ball retainer will receive the end of the pin 13 and the retainer and collar associated therewith will be moved laterally until they are directly in line with the pin 13 thereby automatically centering the two members.

15 A still further advantage arising out of the free movement of the ball retainer and collar is the fact that manufacturing inaccuracies need not be held down to a minimum. No precision in dimensions is demanded by this construction since the parts are freely movable and will automatically regulate themselves to effect the desired result.

20 It will be recognized that a departure of the specific spring mechanism as shown at 22 may be had if desired. It is not necessary to incorporate the yieldable force against the ball retainer and the stop means to limit its outward movement in the same member as has been done here. For example, a different form of spring could be used for this purpose and a separate stop member applied to the ball retainer if so desired.

25 It is also conceived that the pin 13 may be tapered outwardly toward its free end. This will increase the gripping action of the balls 18 making it possible to use a lighter spring 22 if desired and will also prevent any tendency of the balls to slide on the pin. Also, if the closure is not tightly closed any vibration which may occur will cause the balls to ride downwardly on the tapered surface of the pin 13 resulting in eventually automatically bringing the closure to its seat.

30 From the foregoing it will therefore be obvious that we have provided a novel form of ball friction means in order to adapt this type of lock mechanism to a closure member having a swinging movement or one which moves in a fixed path not necessarily in accurate alignment with the pin.

35 Other modes of applying the principle of our invention may be used instead of the one here explained, change being made as regards the structure herein disclosed, provided, however, that the means stated by any of the following claims or the equivalent of such stated means be employed.

We claim:

40 1. A lock of the class described comprising,

a pin, a housing having an opening considerably larger than the pin to receive said pin, friction means within said housing to receive and hold said pin, said friction means being movable laterally of the housing whereby to receive the pin and means extending exteriorly of said housing to release said friction means.

2. A lock of the class described adapted to be affixed to a closure member pivotally mounted in a frame, comprising, a pin attached to the frame, a housing secured to the closure member having a tubular extension thereon passing through said member and adapted to receive said pin, friction means within said housing and movable laterally thereof to receive and hold said pin, and means to release said friction means whereby the closure member may be opened.

3. The combination of elements defined in claim 1, wherein said friction means includes, a plurality of balls between which the pin is received, a ball retainer, a collar surrounding said retainer with a tapered opening therethrough, said collar being laterally movable in said housing, and yieldable means urging the retainer and balls against the sides of the opening through 25 the collar, as specified.

4. A lock of the class described comprising, a pin, a housing having an opening to receive said pin, friction means within the housing to receive said pin and movable longitudinally to release the pin, yieldable means urging the friction means into engagement with the pin, an operating knob extending outside of said housing and means for connecting said knob to said friction means with a limited free longitudinal movement relative to each other.

5. The combination of elements defined in claim 4 wherein said friction means is movable laterally relative to the housing.

6. The combination of elements defined in claim 4 wherein said knob also has a limited free lateral movement relative to the friction means.

7. The combination of elements defined in claim 4 combined with means to stop movement of the knob in the direction of the engagement 20 movement of said friction means at a position intermediate the limits of the free longitudinal connection between said knob and friction means.
